United States Patent Office

Des. 217,874

Patented June 23, 1970

217,874

ROLLER SKATE

Lawrence C. French, 8267 Buffalo Ave.,
Norfolk, Va. 23518

Filed May 6, 1969, Ser. No. 17,033

Term of patent 14 years

Int. Cl. D21—04

U.S. Cl. D34—14

FIG. 1 is a perspective view of the ornamental design of the roller skate according to this invention.

FIG. 2 is a partial perspective view showing the instrument panel in the forward part of the ornamental roller skate according to this invention.

FIG. 3 is a side view of the ornamental roller skate of this invention.

FIG. 4 is a plan view of the ornamental roller skate of this invention.

I claim:

The ornamental design for a roller skate, as shown.
